UNITED STATES PATENT OFFICE.

BENJAMIN LEININGER, OF EAST MCKEESPORT, PENNSYLVANIA.

BABY-WALKER.

SPECIFICATION forming part of Letters Patent No. 761,514, dated May 31, 1904.

Application filed February 15, 1904. Serial No. 193,655. (No model.)

To all whom it may concern:

Be it known that I, BENJAMIN LEININGER, a citizen of the United States of America, residing at East McKeesport, in the county of Allegheny and State of Pennsylvania, have invented certain new and useful Improvements in Baby-Walkers, of which the following is a specification, reference being had therein to the accompanying drawings.

10 This invention has relation to baby-walkers, and has for its object the provision of a device of simple form and construction adapted to sustain an infant in an upright position and permit the infant to move backward and forward by touching its feet to the floor.

15 My invention consists in the combination, with a frame supported on legs, of a sliding board mounted in this frame and having a hole in its center in which the body of the infant is received, the head and arms of the infant being above the board, so that the infant can bear the major portion of its weight upon the board and by touching its feet to the floor propel itself backward and forward.

20 My invention further consists in the combination, with a frame having a slidable board with a hole to receive the body of the infant, of hinged and adjustable legs and means for holding the legs in the adjusted position, so that the frame may be sustained at a greater or less distance from the floor to accommodate the device to infants of different size.

25 In the drawings, Figure 1 is a perspective view of my improvements. Fig. 2 is a longitudinal sectional view of the same. Fig. 3 is a vertical central sectional view, and Fig. 4 is a detail view, of the leg-adjusting devices.

30 In the accompanying drawings, A designates a rectangular frame the sides of which have cleats B fixed upon top of the same, said cleats being formed with slots C C on their inner sides. A flat board D, having an opening F in its center and flanges E E on its front and rear edges, is arranged to slide in the frame, 35 the side edges of the board fitting in the slots C C of the cleats B B. The slots C C in the cleats B B do not extend to the ends of the cleats, but only to a point on a line with the inner sides of the end pieces of the frame, so 40 that the movement of the board D is limited

to the length of the slots in the cleats. The frame A is supported on legs G at each corner, the legs being attached to the bottom of the frame by hinges H H. Cross-pieces I connect the two legs at each end of the frame, and 55 an arm K is secured to the bottom of each end piece of the frame and projects under the cross-pieces I I. The arm K is formed with a slot L, through which is passed a screw M, that is formed with a head N, suitably shaped 60 so as to be easily grasped by the hand.

65 In using the device the infant is sustained by the sliding board D, its head, shoulders, and arms being above the board, and the board thus supports the major portion of the infant's 70 weight and permits the infant to move backward and forward by walking on the floor. The flanges E E serve to keep any toys or other articles in position that may be placed upon the board for the amusement of the child, 75 and the board forms a firm support devoid of projecting portions or movable parts that would cause injury to the child or its garments. The device is shown in its lowermost working position in the drawings, and if it is 80 desired to elevate the frame so as to raise it slightly higher the screws M M are loosened and the legs G G moved inwardly, which will result in their assuming a more nearly vertical position than that shown in the drawings and 85 which will raise the frame more or less, according to the amount of inward movement of the legs. When the legs have been moved so far as is necessary to secure the required elevation of the frame, they are locked in position by 90 tightening up the screws M. If it be desired to remove the device from room to room or store it out of the way, the screws M M may be removed, and this will permit the legs to be folded up flat against the side faces of the 95 frame, so that the latter will occupy but very little space and may be easily handled.

Having fully described my invention, what I claim as new, and desire to secure by Letters Patent, is—

1. In a device of the character described, the combination with a frame and a device slidably mounted therein and adapted to support an infant, of legs hinged to the bottom of the frame, stops on the frame for sustaining the 100

legs in an inclined position and means for securing said legs when moved to different positions on their hinges.

2. In a device of the character described, the combination with a frame, of legs hinged thereto, cross-pieces secured to said legs, slotted arms projecting from the frame beneath said cross-pieces and into the cross-pieces, and screws passing through the slots in the

arms and adapted to hold said legs in the adjusted position, substantially as described.

In testimony whereof I affix my signature in the presence of two witnesses.

BENJAMIN LEININGER.
